UNITED STATES PATENT OFFICE.

ELMER R. BROWN, OF NEW YORK, N. Y.

COMPOUND RAIL.

1,136,585.

Specification of Letters Patent. Patented Apr. 20, 1915.

Application filed July 3, 1914. Serial No. 848,811.

To all whom it may concern:

Be it known that I, ELMER R. BROWN, a citizen of the United States, residing at New York, in the county of New York and State of New York, have invented certain new and useful Improvements in Compound Rails, of which the following is a specification.

My invention relates to new and useful improvements in railway rails of the compound type and has for its primary object to provide a simple, inexpensive and reliable compound rail that is formed of three sections that are held in operative relation to one another in a novel manner so that spreading, sinking or creeping of the rails is prevented, a certain amount of track resiliency provided and an even riding or bearing facilitated.

An object of importance is to provide novel means for securing the rail to a cross tie, said means being of durable and efficient construction and serving to securely hold the sections comprising the rail in operative relation to one another as well as to hold the rail to the tie.

Another object of importance is to provide a rail of the character described that is of simple construction, is light, durable and inexpensive to manufacture and install.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a plan view of my improved rail showing the same attached to fragmentary portions of rail ties, Fig. 2 is a detail sectional view partly in elevation showing the rail securing and holding means

that is employed at the joint of the rails taken on line 2—2 of Fig. 1, Fig. 3 is a detail perspective view partly in section showing one of the members to secure the rail to a tie, said member being constructed similar to the one illustrated in Fig. 2 but smaller, and Fig. 4 is a detail side elevation of the center rail section showing the means for arranging and overlapping the meeting ends of said sections.

Referring to the drawings by characters of reference the numeral 1 designates as an

entirety my improved rail that is mounted in the usual manner upon rail ties 2 by a plurality of rail clamping and securing members 3.

My improved rail consists of a relatively flat center section or strip 4 that is interposed between longitudinal outer sections or strips 5 and 6, each of which is enlarged near its lower edge and beveled on its outer face as at 7, said beveled faces 7 being arranged to coöperate with inwardly inclined flanges 8 formed on opposite sides of the members 3. The flanges 8 form a dove-tail slot which as will be clearly seen securely holds the sections 5 and 6 in position. The upper edges of the sections 4, 5, and 6 are beveled slightly in such manner that the rail-top is sloped or inclined inwardly toward the center of the track, in order to conform to the inclination of the tread surface of an ordinary wheel. Bolts 9 are inserted transversely through the sections 4, 5, and 6 at points centrally, approximately of the upper and lower edges thereof and on opposite sides of each clamping and securing member. The heads of the bolts 9 are arranged to engage the clamping member and the screw threaded terminals thereof have turned thereon suitable nuts 10 which are also arranged to engage the clamping member. This arrangement prevents slipping of the rails. The beveled or inclined outer faces at the lower part of the sections 4 and 5 extend upwardly a distance equivalent to half of the sections. The bolts 9 serve to securely hold the sections 4, 5 and 6 in operative relation to one another.

At the ends of the center section 4 I provide tongues and recesses designated 11 and 12 which form horizontal shoulders to engage one another so as to prevent one end of the center section sinking or slipping relative to the other and provide a more even support at the joint.

At the joints I provide rail securing and clamping members designated 13 as an entirety, each of which consists of a rectangular body plate 14 and having spaced flanges 15 similar to the ones 8 and arranged to coöperate with the beveled enlarged lower edges of the rail sections 5 and 6. Reinforcing ribs 16 are formed on the outer faces of the flanges 15 and a reinforcing rib 17 is formed on the bottom of the plate 14. The rib 17 is designed to fit within a groove which is preferably formed in the tie 2.

Screw threaded spikes 18 are inserted through the plate 14 to secure the member 13 to the tie.

The member 3 is formed identical with 5 the members 13, secured in the same manner to the rail, but is smaller. The flanges 15 on the members 13 extend upwardly for a distance equivalent to half the height of the rail and have their upper faces disposed 10 at a point where the upper edge of the beveled face terminates so as not to interfere with the flanges on the wheels of the cars. This construction and arrangement is provided at the joint so that sinking of one 15 rail relative to the other is obviated and an even track provided.

Should it become necessary to repair or remove one of the sections 4, 5, or 6 it is only necessary to withdraw the bolts 9 and 20 by prying or pushing underneath the rail, force two center sections 4 out of place.

In practice, the rails are laid so that the sections 4, 5 and 6 are not joined at the same place, the joints for the different sections being arranged considerably spaced from each other. In this manner a greater amount of rigidity is provided the track and a smoother bearing surface is provided for the wheels, thus eliminating wear on the 25 wheels and on the trains or cars. At each point where a section is joined with a corresponding section I provide a double tie 19 that is interlocked as at 20 adjacent to its ends. The double tie consists of two 30 ties of the ordinary construction. A securing element 21 is secured about the ties so as to hold them closely together. In this manner it will be readily seen that sinking of one rail section relative to the other is 35 obviated and that an extremely smooth and even bearing surface for the wheels is provided, also possibility of creeping or spreading is obviated.

In a track constructed as described it will 40 be readily seen that more than one independent rail section is arranged to support a wheel thus insuring the smooth and even riding of the rolling stock.

It will be readily seen that the supporting 45 elements of each rail will provide a certain amount of resiliency which could not be had with a solid rail and that different bearing surfaces will serve in a measure to prevent slipping of the rails relative to the track.

The rail securing and clamping members

for holding the rails upon the ties are mounted within recesses in the ties so that the horizontal rail-supporting faces thereof are flush with the faces of the tie and the 60 rails engage a part of each tie as well as the clamping and securing members. This arrangement provides resiliency and serves in a measure to deaden the sound caused by the wheels of the train passing over the 65 rails.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as set forth.

What is claimed is:—

1. A compound rail comprising a flat center section, side sections mounted on the center sections and being enlarged at their lower longitudinal edges and provided with beveled faces on the outer sides of the longitudinal enlarged portions, bolts inserted transversely through the sections, the center section being provided with a recess and a tongue at its ends to coöperate with the ends of adjacent sections at the joint and means 85 to engage the beveled enlarged portions of the outer sections, to hold the sections in operative relation to one another and secure the rail to a tie.

2. A compound rail consisting of a plurality of sections, means to secure the sections to one another, each of said sections being beveled at its upper edge to provide a slope to the upper face of the rail and means to clamp the sections in operative relation, 100 the central sections being provided with tongues and recesses at their ends, and means to secure the rail to a tie, also serving to hold the sections in operative relation to one another.

In testimony whereof I affix my signature in presence of two witnesses.

ELMER R. BROWN.
